UNITED STATES PATENT OFFICE.

WILLIAM F. HELMOND, OF HARTFORD, CONNECTICUT, ASSIGNOR TO UNDERWOOD TYPE-WRITER COMPANY, OF NEW YORK, N. Y., A CORPORATION OF NEW JERSEY.

TYPE-WRITING MACHINE.

No. 897,366.

Specification of Letters Patent.

Patented Sept. 1, 1908.

Application filed February 8, 1908. Serial No. 414,871.

To all whom it may concern:

Be it known that I, WILLIAM F. HELMOND, a citizen of the United States, residing in Hartford, in the county of Hartford and 5 State of Connecticut, have invented certain new and useful Improvements in Type-Writing Machines, of which the following is a specification.

This invention relates to the releasable pressure 10 rolls of typewriting machines, and particularly to machines of the well known Underwood type.

The object of the invention is to provide a simplified, improved and cheapened pressure 15 roll mechanism.

I hang the front and rear pressure roll shafts upon rock arms, which are engaged by leaf springs to press the rolls against the platen; each spring being supported at its 20 middle, and near each end engaging its rock arms. The springs are disposed opposite each other, and I arrange a key-operated rock shaft extending between said springs and parallel with the platen and having cams 25 to engage the tips of the springs. The described mechanism is mounted upon a sheet metal plate, which is secured at its ends to the ends of the platen frame, and has at its upper edge recesses to receive the rock arms; 30 the latter mounted in pairs upon pivots or pintles which are attached to the supporting plate.

Other objects and advantages will herein-after appear.

In the accompanying drawings, Figure 1 is a front elevation of the platen frame and platen of an Underwood typewriting machine, showing my improvements applied thereto; the parts being in normal positions. Fig. 2 35 is an inverted plan of a portion of the roll-releasing mechanism at one end of the machine. Fig. 3 is an end elevation showing the release-key depressed, and the pressure rolls mechanically held away from the platen. Fig. 4 is a view similar to Fig. 3, but showing the parts in normal positions. Fig. 5 is a 40 detail to illustrate the manner in which the roll-releasing rock-shaft is mounted upon the platen frame. Fig. 6 is a detail to be 45 read in connection with Fig. 3, to show the action of the roll carrying-arms.

In said Underwood typewriting machine, a platen 1 is revolubly mounted in a platen

frame whose ends are seen at 2; the writing being done upon the front of the platen by 55 type bars 3. Front and rear pressure rolls 4, 5 are arranged to run upon the under side of the platen. Said rolls are carried upon shafts 6, 7, the front shaft carried in arms 8, and the rear shaft in arms 9, the shafts being 60 detachable from the arms.

Springs 10, 11 arranged opposite each other, are secured at their middle portions by screws 12, 13, and extend in each direction along the platen, and near their free ends 65 bear respectively upon fingers 14, 15, formed upon said arms 8, 9, respectively, to press the rolls against the platen. Said screws 12, 13 attach said springs to brackets 16, 17, which are secured upon the front and rear faces of 70 a main supporting plate or bar 18, which is secured at its ends to the platen frame ends 2 in any suitable manner. Said plate is recessed at its upper edge at 19 to receive the hubs of each of two pairs of arms 8, 9, said 75 arms being pivoted upon pintles 20 secured by screws 21 to the plate, the screws being transversely threaded into said pintles, and each of the latter forming a bridge across the recess 19. 80

A release-key 22 upon the right hand platen frame end is connected by a link 23 to a crank 24 formed upon a rock shaft 25. The supporting-plate 18 is fluted at 26 to receive and form bearings for said rock shaft, 85 the latter being retained by keepers 27 at the ends of the plate. Upon said rock shaft are secured collars 28 upon each of which is formed a double cam 29 to engage tips 30 turned in from the ends of the springs 10, 11, 90 said cams operating when the finger-key 22 is depressed, to spread the springs apart, Fig. 2, and release the fingers 14, 15, so that the rolls 4, 5 drop from the platen, Fig. 3. Each cam 29 is formed upon its end with a flat 95 or rest 31 to engage the tip of the spring, and hold the latter mechanically in the Fig. 2 and 3 position, when the key is depressed, so that the rolls are mechanically detained in released positions. 100

To regulate the tension of the springs, screws 32 are employed, said screws having heads 33 to engage one spring, and the shanks of the screws being threaded through the opposite spring, so that the tension of both 105 springs may be regulated by turning up one

screw at either side of the brackets 16, 17; the screws passing through openings 34 in the plate 18.

Having thus described my invention, I 5 claim:

1. In a typewriting machine, the combination with a revoluble platen and a platen frame, of a releasable pressure-roll mechanism including a plate or bar extending along 10 the platen and fixed at its ends to the ends of the platen frame, a rock-shaft journaled upon said plate and extending along the platen, a key connected to said rock-shaft, cam collars upon said rock shaft, leaf springs secured 15 upon said plate and engageable by said cam collars, and arms carrying pressure-rolls and engageable by said springs and pivoted on said plate.
2. In a typewriting machine, the combination with a revoluble platen and a platen frame, of a releasable pressure-roll mechanism including a plate or bar extending along 20 the platen and fixed at its ends to the ends of the platen frame, a rock-shaft journaled upon said plate and extending along the platen, a key connected to said rock-shaft, cam collars upon said rock shaft, leaf springs secured 25 upon said plate and engageable by said cam collars, and arms carrying pressure-rolls and engageable by said springs and pivoted on said plate.
3. In a typewriting machine, the combination with a revoluble platen and a platen frame, of a releasable pressure-roll mechanism including a plate or bar extending along 30 the platen and fixed at its ends to the ends of the platen frame, a rock-shaft journaled upon said plate and extending along the platen, a key connected to said rock-shaft, cam collars upon said rock shaft, leaf springs secured 35 upon said plate and engageable by said cam collars, and arms carrying pressure-rolls and engageable by said springs and pivoted on said plate; said arms being arranged in pairs, and a pintle being fixed upon said plate to carry each of said pairs of arms.
4. In a typewriting machine, the combination with a revoluble platen and a platen frame, of a releasable pressure-roll mechanism including a plate or bar extending along 40 the platen and fixed at its ends to the ends of the platen frame, a rock-shaft journaled upon said plate and extending along the platen, a key connected to said rock-shaft, cam collars upon said rock shaft, leaf springs secured 45 upon said plate and engageable by said cam collars, and arms carrying pressure-rolls and engageable by said springs and pivoted on said plate; said plate having recesses in its edge to receive the arms, and said recesses being bridged by pintles upon 50 which the arms are pivoted.
5. In a typewriting machine, the combination with a revoluble platen and a platen frame, of a releasable pressure-roll mechanism including a plate or bar extending along 55 the platen and fixed at its ends to the ends of the platen frame, a rock-shaft journaled upon said plate and extending along the platen, a key connected to said rock-shaft, cam collars upon said rock shaft, leaf springs secured 60 upon said plate and engageable by said cam collars, and arms carrying pressure-rolls and engageable by said springs and pivoted on said plate; each of said springs being secured at its middle portion to a bracket 65 attached to the plate, one bracket upon each

side of the plate, and the rock-shaft extending between the springs.

5. In a typewriting machine, the combination with a revoluble platen and a platen frame, of a releasable pressure-roll mechanism including a plate or bar extending along 70 the platen and fixed at its ends to the ends of the platen frame, a rock-shaft journaled upon said plate and extending along the platen, a key connected to said rock-shaft, cam collars upon said rock shaft, leaf springs secured 75 upon said plate and engageable by said cam collars, and arms carrying pressure-rolls and engageable by said springs and pivoted on said plate; each of said springs being secured at its middle portion to a bracket attached to the plate, one bracket upon each 80 side of the plate, and the rock-shaft extending between the springs; and means being provided to regulate the tension of the springs, said regulating means comprising screws each having a head to engage one spring and a shank threaded through the opposite spring.

6. In a typewriting machine, the combination with a revoluble platen and a platen frame, of a releasable pressure-roll mechanism including a plate or bar extending along 90 the platen and fixed at its ends to the ends of the platen frame, a rock-shaft journaled upon said plate and extending along the platen, a key connected to said rock-shaft, cam collars upon said rock shaft, leaf springs secured 95 upon said plate and engageable by said cam collars, and arms carrying pressure-rolls and engageable by said springs and pivoted on said plate; said cam collars provided 100 with rests to engage the springs and hold them mechanically in released positions.

7. In a typewriting machine, the combination with a revoluble platen and a platen frame, of a releasable pressure-roll mechanism including a rock-shaft, a key connected to said rock-shaft, cams upon said rock shaft, leaf springs engageable at their tips by said 110 cams, and arms carrying pressure-rolls and engageable by said springs; each of said springs being supported at its middle portion, one upon each side of the rock-shaft.

8. In a typewriting machine, the combination with a revoluble platen and a platen frame, of a releasable pressure-roll mechanism including a rock-shaft, a key connected to said rock-shaft, cams upon said rock shaft, leaf springs engageable at their tips by said 120 cams, and arms carrying pressure-rolls and engageable by said springs; each of said springs being supported at its middle portion, one upon each side of the rock-shaft; screws being provided to regulate the tension of the 125 springs, each screw having a head to engage one spring, and a shank threaded through the opposite spring.

9. In a typewriting machine, the combination with a revoluble platen and a platen 130

- frame, of rolls, arms carrying said rolls, a rock-shaft, a key connected to said rock-shaft, cams upon said rock-shaft, opposite leaf springs pressing said arms and engageable at 5 their tips by said cams, and screws to regulate the tension of the springs, said screws each having a head to engage one spring and a shank threaded through the opposite spring.
- 10 10. In a typewriting machine, the combination with a revoluble platen and a platen frame, of a releasable pressure-roll mechanism including a rock-shaft, a key connected to said rock-shaft, cams upon said rock-shaft, 15 leaf springs engageable at their tips by said cams, and arms carrying pressure-rolls and engageable by said springs; each of said springs being supported at its middle portion, one upon each side of the rock-shaft; said 20 cams formed on their ends with rests to engage the springs and hold them mechanically in released positions.
11. In a typewriting machine, the combination with a revoluble platen and a platen frame, of pressure rolls to run upon the 25 platen, a key connected to a rock-shaft, cams
- secured upon said rock-shaft, opposite leaf springs engageable by said cams, and arms carrying said rolls and operable by said springs; each of the springs being secured at 30 its middle portion upon a support carried by the platen frame, and said rock-shaft extending along the platen between the springs.
12. In a typewriting machine, the combination with a revoluble platen and a platen 35 frame, of pressure rolls to run upon the platen, a key connected to a rock-shaft, cams secured upon said rock-shaft, opposite leaf springs engageable by said cams, and arms carrying said rolls and operable by said 40 springs; each of the springs being secured at its middle portion upon a support carried by the platen frame, and said rock-shaft extending along the platen between the springs; and screws to regulate the tension of the 45 springs, each screw engaging one spring and having a shank threaded through the opposite spring.
